US00D507200S

(12) **United States Design Patent** (10) Patent No.: **US D507,200 S**
Adrianson et al. (45) Date of Patent: **** Jul. 12, 2005**

(54) **FINGERPRINT SENSING SECURITY DEVICE**

(75) Inventors: **Alan Ashley Adrianson**, Taylor, MI (US); **Leslie Kirk Walters**, Shelby Township, MI (US); **David A. LaVoy**, Southgate, MI (US); **David Burke**, Taylor, MI (US)

(73) Assignee: **Masco Corporation**, Taylor, MI (US)

(**) Term: **14 Years**

(21) Appl. No.: **29/197,255**

(22) Filed: **Jan. 13, 2004**

(51) LOC (8) Cl. **10-05**

(52) U.S. Cl. **D10/104**

(58) Field of Search D10/104, 46; D14/105, D14/384, 392; 382/124, 125, 126, 312; 438/48, 98

(57) **CLAIM**

The ornamental design for a fingerprint sensing security device, as shown and described.

DESCRIPTION

FIG. 1 is a perspective view of a fingerprint sensing security device showing our new design;

FIG. 2 is a front elevational view thereof;

FIG. 3 is a left side view thereof, the opposite side being a mirror image of the side shown;

FIG. 4 is a top plan view thereof; and,

FIG. 5 is a bottom plan view thereof.

The broken line showing of FIGS. 1-5 is for illustrative purposes only and forms no part of the claimed design.
